UNITED STATES PATENT OFFICE.

CHARLES M. LUNGREN, OF NEW YORK, N. Y.

GAS-BURNER.

SPECIFICATION forming part of Letters Patent No. 365,831, dated July 5, 1857.

Application filed July 31, 1881. Serial No. 139,293. (No model.)

To all whom it may concern:

Be it known that I, CHARLES M. LUNGREN, a citizen of the United States, and a resident of New York, in the county of New York and State of New York, have invented certain new and useful Improvements in Gas-Burners, of which the following is a specification.

My invention consists in the novel construction and combinations of parts making up the improved gas-lamp described in the following specification. The novel features and combinations will be more particularly described in the claims.

In the accompanying drawings, Figure 1 is a longitudinal section of a form of burner constructed in accordance with my invention. Fig. 2 is a cross section on the line XX of Fig. 1. Fig. 3 shows a burner with a modified form of flame-tube. Fig. 4 shows a cluster of burners depending from a common pipe or chimney. Fig. 5 shows a flattened flame-tube with a number of gas-tips arranged side by side. Fig. 6 shows a modified form of the transparent or translucent flame-tube. Fig. 7 illustrates another way in which a flame-tube suited to the purposes of my invention may be constructed.

Referring to Figs. 1, 2, 3, and 4, A indicates a pipe or flue, preferably of metal, forming an escape-flue for the heated products of combustion from the burner, and B an outer shell, between which and the flue A is a space for the passage of air to the flame.

The burner is of any desired form or construction, according to the shape of the translucent tube D with which it is employed, and may have a single jet or a number of separate jets arranged in proper relation to give a round, flat, or otherwise shaped flame.

The burner is supplied with gas or other inflammable substance through a pipe, G G', a portion of which is preferably carried through or in close proximity to the escape-flue A, so that the material consumed will be heated before reaching the burner proper.

D indicates a flame tube or pipe of transparent or translucent material, and of any desired form in cross-section, connected at its end removed from the burner proper with the chimney A. The end of the tube D near the burner is attached in any desired manner to the lower

end of the flue A, or to a lateral or downwardly-projecting extension therefrom, or to any other desired support. This end of the tube is cut off from the chimney A by a diaphragm or partition, m, of any desired form or construction. Air is supplied to the burner E and the flame, in whole or in part, through openings n from the space between A and B. This air-supply is furnished to the latter space through openings p in the shell B, and in its progress to the burner the air becomes heated by the products of combustion escaping through the flue A. The tube D might be flattened, as indicated in Fig. 5, and the burner E be constructed from a number of separate jets, or it might be circular in form and have an inner tube or rod, as indicated at r, Fig. 7, so as to form an annular flame-space, the burner-jets being in this case arranged in a circular row, as indicated. The tube D may be made detachable in any desired manner, to permit lighting, or the burner may be lighted by applying flame at the mouth of the flue or chimney A. A division-plate, a, is located, as shown, in the space between the walls of A and B, so as to compel the air entering at the perforations p to pass indirectly to the openings n, and to thus be more thoroughly heated. The gas supplied to the burner is heated as it passes through the tube G. The gas-pipe G' extends through a bracket supporting the burner, or itself constitutes the bracket.

Fig. 4 shows a cluster of burners attached to a common shell or support, B. It is not necessary that the tube D should be wholly translucent. It may be translucent on one side only, or that in which illumination is desired. It may therefore be made in the way indicated in Fig. 8, where A² indicates a cup-shaped piece of glass, and B² a piece of refractory material—such as porcelain, asbestos, or metal—secured in the cup so as to leave a tubular way for the flame.

It is obvious that a burner of the kind described may be used in any desired position, and that it might be set upright or in position the reverse of that shown in Figs. 1 and 2, or that it might be turned and used in a position ninety degrees removed from that shown. It is therefore to be understood that the terms "downwardly," "upwardly," "depending,"

&c., as used herein, are not used in their absolute sense, but only to express the position or relation of the parts in a burner in the position shown in the drawings, and I employ them as applying to any burner in which, if the burner be set in the position indicated, the relation defined would exist.

What I claim as my invention is—

1. The combination, substantially as described, of a curved transparent or translucent flame tube, a gas-burner above the flame-tube and adapted to deliver a jet of gas into said tube in a direction substantially coinciding with the axis thereof, a chimney or escape-flue above the burner and flame-tube, and a connection between the base of the chimney and the end of the flame-tube opposite that at which the burner is located.
2. A regenerative gas-lamp consisting, substantially, of a chimney or escape flue, a gas-burner supported at or near the base of the chimney, a depending curved transparent flame-tube encircling at one end the gas-orifice and having its other end carried around for connection with the base of the chimney, and air-passages for supplying air to the flame carried in proximity to the passages for the escaping products of combustion.
3. A gas-lamp consisting, essentially, of an escape-flue or chimney, a gas-burner located or supported at or near the base thereof, a depending curved transparent flame-tube, one of whose ends encircles the burner-tip, while its other end connects with the base of the chimney, an air-casing surrounding the escape-flue, and an inlet-passage connecting the space

between said casing and escape-flue with the end of the flame-tube into which the burner delivers the gas.

4. The combination, with a gas-burner, of a 40 transparent or translucent flame tube or pipe, an escape-flue or chimney placed above or at the opposite side of the gas-burner from the flame-tube, and a connection between the base of the chimney and the end of the flame-tube 45 removed from the burner, as and for the purpose described.

5. A gas-lamp consisting, essentially, of a forked or branched tube forming the escape-flue or chimney, a gas-burner supported in 50 one of the branches, a curved transparent flame-tube connecting the ends of the two branches, and a diaphragm or wall between the end of the flame-tube into which the burner delivers the gas and the portion of the chimney through which the escaping products of combustion pass.

6. A gas-lamp consisting, essentially, of an escape-flue or chimney, a gas-burner at or near the base thereof, and a depending flame-tube 60 connected at one end with the space into which the burner delivers the gas and at the other end with the base of the chimney, as and for the purpose described.

Signed at New York, in the county of New 65 York and State of New York, this 28th day of July, A. D. 1884.

CHARLES M. LUNGEN.
